UNITED STATES PATENT OFFICE

ADELBERT E. BRONSON, OF CLEVELAND, OHIO, ASSIGNOR TO THE DILL MANUFACTURING COMPANY, OF CLEVELAND, OHIO, A CORPORATION OF OHIO

QUICK-DETACHABLE DUST CAP

Application filed May 6, 1925. Serial No. 28,334.

The present invention relates to a dust cap which is primarily intended for use with pneumatic valve stems for air inflated articles, such as tires, inner tubes and the like.

5 The object of the invention is to provide a quick detachable dust cap in which the usual form of valve cap serves as a means for attaching the dust cap to the valve stem and in which construction a binding effect is produced so as to hold the dust cap and valve cap in any adjusted relation with respect to each other.

10 A further object is to provide a dust cap with attaching means to cooperate with the usual valve cap, so that the dust cap and the attaching means may be manufactured and sold as a distinct article, which may be taken by a purchaser and attached to a valve cap, which he already possesses, thereby creating a combined closure for the valve stem and a quick detachable dust cap.

15 Reference should be had to the accompanying drawings forming a part of this specification, in which Fig. 1 is an elevation of a dust cap with portions in section and showing a valve cap mounted within the dust cap; Fig. 2 is a section upon the line 2-2 of Fig. 1; Fig. 3 is a top plan view of a portion of the device; Fig. 4 is an end elevation with portions in section of the showing in Fig. 3; Fig. 5 is another top plan view of another portion of the device; Fig. 6 is an elevation of the showing in Fig. 5, and Fig. 7 is a sectional elevation of the device shown in Figs. 5 and 6.

20 Referring to the drawings, 1 indicates a dust cap or shell, which is hollow and closed at one end by a dome-shaped closure 2 and open at the opposite end. The shell may be formed in any desired manner, and is preferably supplied with a plurality of flat sides, such as indicated at 3.

25 Within the shell 1 is an expanding member 4, the outer surface of this expanding member being adapted to fit within the shell 1, and where the shell is provided with a plurality of flat sides, as before described, the outer surface of the member 4 will be provided with a similar number of flat sides in complement to the shell.

The member 4 is split as indicated at 5, and when inserted in the shell 1, will be compressed so that after insertion the member 4, in expanding, will be in close frictional contact with the inner surface of the shell 1.

30 The inner surface of the member 4 is elliptical in form having an undercut groove, as indicated at 6 in Figs. 1 and 4, and this is adapted to receive a member 7, as shown in Figs. 5, 6 and 7. This member 7 is provided with a substantially annular extension 7^a elliptical in form, which is adapted to fit in the undercut groove 6 so that when the members 4 and 7 are assembled they will be held together by the engagement of the extension 7^a in the groove 6. The member 7 is split, as indicated at 7^b so that it may be slightly compressed. The member 7 is inserted within the member 4, and both members are put under slight compression when they are inserted in the shell 1. After insertion and the compressing means or force, is relieved, then the members 7 and 7^a will expand so that there will be a close frictional contact between the member 7 and the member 4, and likewise a close frictional contact between the outer surface of the member 4 and the inner surface of the member 1.

35 It will also be apparent that relative movement between the members 4 and 7 will, due to the elliptical surfaces, cause the expansion of the member 4 into what may be termed locked relation with the shell 1.

40 The member 7 is provided with an inside groove 8 which is roughened or provided with serrations and in this groove 8 there is inserted a valve cap 9 which may be of usual construction. Such a valve cap has an upwardly extending portion 10 having a slot 11 thereby forming the usual screw driver provisions, and is also provided with an extending annular portion on the body thereof, as indicated at 12, which has its outer surface knurled or provided with vertical serrations.

45 When the valve cap 9 is inserted within the member 7 the knurled portion 12 of the valve cap occupies the groove 8. Due to the engagement of the roughened surfaces of the groove 8 and the portion 12 of the valve cap there

will be no relative turning between the member 7 and the valve cap 9.

The valve cap within the lower portion thereof which is indicated at 13 in the drawing, is provided with interior threads and a packing member, as is usual in such valve caps, and will need no description here.

In using the device, the shell 1 is passed over the end of a valve stem until the end of the valve stem engages with the threaded portion of the valve cap 9. When this takes place the dust cap 1 is rotated, and by virtue of such rotation and the character of the members 4 and 7 which cooperate with the valve cap 9, the valve cap 9 will also be caused to rotate and so be threaded upon the end of the valve stem.

When the valve cap 9 has been turned on the valve stem as far as it will go, the valve cap 9 will then be stationary, and continued rotation of the dust cap or shell 1 will cause relative rotation between the member 4 and the member 7, and this in turn will cause an expansion of the member 4 so that the member 4 is expanded into even closer and tighter engagement with the shell 1, thereby locking the stem, valve cap 9, and dust cap 1, so that they are held against relative movement.

In introducing a dust cap constructed as above described, upon the end of a valve stem, the dust cap structure, with the valve cap on the inside thereof, will be turned onto the valve stem the distance of a few threads, and when the dust cap is pushed inwardly the lower end of the dust cap contacts with the rim nut which is usually employed to secure the valve stem in place upon the rim of a wheel, or in the event that such rim nut is omitted, the shell may be pushed directly against the felly of the wheel. Thereupon dust cap is given further rotation to obtain the locking or fastening action of the dust cap, valve cap and stem which has before been discussed.

The lower or open end of the dust cap is unobstructed so that it is possible to remove the members 4, 7 and the inclined valve cap 9, out of the end of the dust cap. This may be done whenever it is desired to utilize the valve cap 9 as a tool for the purpose of inserting the valve insides in the valve stem. Under such circumstances, all that is necessary is to partially thread the valve stem into the valve cap 9, and then pull the dust cap and the valve stem apart so that the valve cap with the members 7 and 4 will be pulled out of the end of the dust cap, whereupon the valve cap 9 may be removed from the end of the valve stem and used as a tool in the manner before described. The parts may then be re-assembled by compressing the members 7, 4, so as to insert them in the dust cap 9. The above construction provides a quick detachable dust cap combined with a valve cap

which may be manufactured at low cost, at the same time provides a construction in which the valve cap not only closes the end of the valve stem, but forms in connection with parts with which it co-operates, the means by which the dust cap is frictionally attached to the valve stem. This construction also obviates the necessity for threading a dust cap through the entire length of a valve stem, projecting beyond the felly of the wheel, as is necessary at present with usual forms of dust caps.

Furthermore, the construction of dust cap and internal friction members, may be manufactured and sold together, without a valve cap being assembled therewith. This will enable a purchaser to use a valve cap which he may have on hand, and which is furnished as standard equipment with valve stems for tires.

The above will enable a purchaser to secure a quick detachable dust cap at low cost.

Having described my invention, I claim:

1. A dust cap construction comprising a shell open at one end, a valve cap within said shell, expandible means cooperatively associated with the valve cap and interior wall of the shell, said expandible means and said valve cap having cooperating surface contours whereby relative rotation of the expandible means and the valve cap causes expansion of said means to frictionally lock the same to the shell.

2. A dust cap construction comprising a shell open at one end, a valve cap within said shell, a member engaging the valve cap, the outer surface of said member being elliptical, an expandible member engaging the inner wall of the shell, said expandible member having an elliptical inner surface cooperating with the outer surface of the first mentioned member, whereby relative movement of the members causes frictional engagement of the expandible member with the wall of the shell.

3. A dust cap construction comprising a shell open at one end, a valve cap within said shell, an expandible member engaging the inner wall of the shell, a second member interposed between the expandible member and the valve cap and fixed with respect to the latter, said members having cooperating surface contours whereby relative rotation of the members causes frictional engagement of the expandible member within the wall of the shell.

4. A dust cap construction comprising a shell open at one end, a valve cap within said shell, said valve cap being provided with a surface which is roughened, a member embracing the valve cap and having its interior surface roughened and cooperating with the roughened surface of the valve cap, an expandible member relatively rotatable with respect to the first mentioned member, said

members having cooperating surface contours such that when said members are relatively rotated the expansible member will be expanded into frictional locking engagement with the shell.

5 In testimony whereof, I hereunto affix my signature.

ADELBERT E. BRONSON.
